(57) **CLAIM**

The ornamental design for a convoluted tube overmold on a din connector, as shown and described.

DESCRIPTION

FIG. 1 is a perspective view of a convoluted tube overmold on a din connector showing my new design;

FIG. 2 is an end view thereof;

FIG. 3 is an opposite end view thereof;

FIG. 4 is a side view thereof, the opposite side being a mirror image;

FIG. 5 is a top view thereof; and,

FIG. 6 is a bottom view thereof.

The broken lines in FIGS. 1-4 and 6 are included for the purpose of illustrating environmental structure only and form no part of the claimed design.
